Inventor:

Andrew J. Wheeler

UNITED STATES PATENT OFFICE.

ANDREW JACKSON WHEELER, OF COMANCHE, TEXAS.

DESIGN FOR A CAM-WHEEL.

SPECIFICATION forming part of Design No. 28,354, dated March 8, 1898.

Application filed November 18, 1897. Serial No. 659,045. Term of patent 14 years.

To all whom it may concern:

Be it known that I, ANDREW JACKSON WHEELER, a citizen of the United States, residing at Comanche, in the county of Comanche and State of Texas, have invented a new and original Design for a Cam-Wheel, of which the following is a specification.

This invention relates to a new and original design for a cam-wheel; and it has for its object to provide a design of this character that shall be both useful and ornamental.

The leading feature of the design resides in a cam-wheel having opposite reversely-disposed duplicate lobes of a segmental form, each provided with a straight and an approximately semicircular curved side, the curved side of one lobe curving from the outer extremity of its straight side into the inner extremity of the straight side of the other lobe, and the straight sides of the two lobes lying in parallel planes.

A minor feature of the design resides in providing the duplicate segmental lobes with inner beveled side edges and with skeleton webs having straight beveled ribs disposed tangentially to the axis of the wheel and also having sector and segmental shaped figures located, respectively, at opposite sides of said ribs.

An additional minor feature is to provide the cam-wheel at the central portion thereof where the two lobes intersect with a rectangular block portion.

In the drawings, Figure 1 is a perspective view of a cam-wheel embodying the herein-described design. Fig. 2 is a plan view thereof. Fig. 3 is a side edge view of the cam-wheel.

Referring to the accompanying drawings, the numeral 1 designates a cam-wheel having 40 opposite reversely-disposed duplicate lobes 2. These duplicate lobes are of a segmental form and each provided with a straight side 3 and an approximately semicircular curved side 4. The curved side 4 of each lobe 2 curves from 45 the outer extremity of the straight side 3 of the lobe into the inner extremity of the straight side 3 of the other lobe, the point where the straight and curved sides of the opposite lobes merge into each other being 50 indicated by the numeral 5. By reason of the relation of the straight and curved sides described it is to be observed that the straight sides 3 of the two lobes lie in parallel planes.

The duplicate lobes 2 of the wheel are provided with inner beveled side edges 6 and with skeleton webs 7. The skeleton web 7 within each lobe 2 is provided with a straight beveled rib 8, disposed tangentially to the axis of the wheel, and with sector and segmental shaped figures 9 and 10, located, respectively, at opposite sides of said rib 8.

The design is completed by providing the wheel at its central portion with a rectangular block 11 and a cylindrical axle 12. 65

What I claim is—

The design for a cam-wheel, herein shown and described.

In testimony that I claim the foregoing as my own I have hereunto affixed my signature 70 in the presence of two witnesses.

ANDREW JACKSON WHEELER.
